UNITED STATES PATENT OFFICE.

MILTON IVES PARKHURST, OF FANCY PRAIRIE, ILLINOIS.

DRAFT-COMPENSATING DEVICE.

No. 849,265.

Specification of Letters Patent.

Patented April 2, 1907.

Application filed November 11, 1905. Serial No. 286,902.

To all whom it may concern:

Be it known that I, MILTON IVES PARKHURST, a citizen of the United States, residing at Fancy Prairie, in the county of Menard 5 and State of Illinois, have invented new and useful Improvements in Draft-Compensating Devices, of which the following is a specification.

The invention relates to an improvement in draft-compensating devices for use in connection with binders, harvesters, or the like.

The main object of the present invention is the production of means for equalizing the draft and supporting the weight of the frame; and to this end the invention consists in certain details of construction and combinations of parts, which will be described in the following specification, reference being had to the accompanying drawings, in which—

20 Figure 1 is a plan view illustrating the application of my improved compensating device to the binder. Fig. 2 is an enlarged side elevation, partly in section, illustrating means for coupling the tongue to the binder and the adjustability of said tongue with relation to the frame. Fig. 3 is a vertical sectional view of the tongue-coupling. Fig. 4 is a longitudinal section of the tongue draw-head, the latter being shown in place therein. Fig. 5 is a vertical sectional view, partly in elevation, of one of the spring compensating members. Fig. 6 is a view in elevation, partly in section, of the truck-support for the frame.

35 Referring to the drawings, wherein like reference-numerals indicate like parts throughout the several views, 1 represents the binder, which so far as the purposes of the present invention are concerned may be made of any 40 desired construction.

2 represents what I term a "tongue-coupling," comprising a box-like member having laterally-projecting plates 3, designed to be bolted or otherwise secured to the side bar 4 of the binder-frame. The coupling is set, preferably, vertical relative to the normal position of the frame and is preferably open at top to permit the ready introduction of the tongue. The side walls of the coupling are 45 formed with a series of alined openings 5, designed to receive a coupling-pin 6, adapted for passage through an opening in the tongue, as hereinafter explained, whereby said tongue is secured to the coupling.

55 The tongue 7, which may be of any length desired or necessary, is designed to be insert-

ed laterally within the coupling 2 and to be secured therein by the pin 6 passing through the alined holes of the coupling and through an opening 9, formed in the tongue, thereby 60 supporting the tongue at the height desired. The rear end of the tongue is provided with an arm 10, removably secured by a bolt 11 and formed with an arrow-head end. This arm is arranged for coöperation with a guide 65 12, secured to the strip 4 of the binder and comprising a vertically-extending casing 13, approximately triangular in cross-section and open at front to receive the arrow-head, whereby the tongue is prevented from becoming accidentally disengaged from its connection with the binder during its adjustment, as will be obvious, it being understood that the guide 12 is so disposed and of such size in practice as to receive the arrow end of 70 the tongue in any connected position of the tongue relative to the coupling.

14 represents what I term the "draw-head," being a rectangular box-like structure open at the ends and designed to slidably embrace the tongue 7. The draw-head is connected with the tongue and limited in its movement thereon through the medium of a pin 15 passing through the upper and lower walls of said draw-head and engaging a 80 85 longitudinally-arranged slot 16, formed in the tongue. From the rear end of the draw-head arms 17 and 18 are projected in opposite direction, preferably inclining toward the rear of the tongue. These arms are exact 90 duplicates in length and inclination and are each formed with a series of holes 19, extending longitudinally of the arms. An arm 20 projects laterally from the forward end of the coupling 2 and is formed with a series of 95 openings 21, spaced longitudinally thereof.

The compensating devices proper comprise duplicate casings, each including cylindrical members 22 23, arranged for threaded connection end to end, as at 24, the adjacent 100 ends of the members being open, while their remote ends are closed or headed. This construction provides a cylindrical casing having closed ends, in which is mounted springs 25 26. Each of the springs encircle rods 27 105 28, respectively, which at their inner or adjacent ends are provided with heads 29, against which the inner ends of the springs bear, the outer or remote ends of the springs bearing against the respective heads of the 110 casing. The outer or remote ends of the rods 27 28 project, respectively, through the

opposite heads of the casing and are terminally provided with hooks 30 31.

In my invention I utilize one of the compensating devices described on each side of the tongue, the forward end of the device on the side of the tongue next the binder-frame being removably connected in one of the openings 19 in the arm 17 through the junction of the hook 31 therewith, while the rear end of said device is connected, through the medium of the hook 30, to an eyebolt 32, secured to the forward frame-bar of the binder. The opposite compensating device is similarly connected, through the medium of its hooks 30 and 31, to the arms 20 and 18, projecting, respectively, from the coupling 2 and draw-head 14. By virtue of the openings 19, formed in the arms 17 and 18, the forward ends of the compensating devices may be adjusted relative to the draw-head, thus increasing or decreasing the tension of the springs 25 26 within the casings in an obvious manner. By preference the spring 25 on the same side of the tongue as the evener 25 is of materially greater strength than the spring on the opposite side, as it is at once obvious that the compensating strain of said former spring is necessarily greater than that of the latter spring.

The four-horse evener 33 is secured to the draw-head 14 preferably through the medium of a pin 15, and to the free ends of the evener are secured the usual two-horse eveners 34.

In connection with the equalizer described I arrange a truck for supporting the frame of the binder when the same is not under draft, said truck comprising a casting 35, secured to the forward frame-bar of the binder and formed with a vertically-arranged opening 36, in which is revolvably and slidably mounted a stem 7, carrying at its lower end a yoke 38, in which is mounted a ground-wheel 39. Adjacent the yoke the stem 37 is provided with a collar 40, between which and the lower end of the casting is secured a coil-spring 41. This truck is primarily designed for supporting the front of the binder when the team is standing or turning and at no other time, as the springs will support all the weight when in motion. The spring on the truck will prevent the contact of the truck-wheel from elevating the machine by contacting with an elevation on the ground while the machine is in motion, as said spring will permit a yielding of the wheel without affecting the frame of the binder.

In operation the compensating devices are to be adjusted by changing the connection of the hooks 31 with the arms 17 and 18 until the tongue is free of binding contact with the draw-head, it being obvious that if such compensating devices are of equal tension the forward draft of the teams will cause a lateral binding of the draw-heads upon the

tongue. The hooks 31 may be engaged with one or the other of the holes 19 in the arms 18, so that the draw-head will move without lateral binding on the tongue. The tongue is now adjusted longitudinally to give it such elevation as will compensate for the pull of the springs and insure that the weight of the binder is carried by the draft of the team.

From the construction described it will be seen that the compensating springs compensate for the draft of the binder and that the longitudinal adjustment of the tongue practically supports the weight of the machine by the draft of the team.

Having thus described the invention, what I claim as new is—

1. The combination with a binder or the like, of a tongue movably secured thereto, a draw-head movably mounted on the tongue and supporting the draft-eveners, and compensating devices on opposite sides of said tongue and connected to the draw-head and to the binder, said compensating devices being respectively of normally unequal strengths.

2. The combination with a binder, of a coupling secured thereto, a tongue adjustably supported in the coupling, a draw-head slidably engaging the tongue and supporting the draft-eveners, and compensating devices connected to the binder and to the draw-head, said compensating devices being respectively of normally unequal strengths.

3. The combination with a binder, of a coupling secured thereto, a tongue adjustably supported in the coupling, a draw-head slidably engaging the tongue and supporting the draft-eveners, and compensating devices connected to the binder and to the draw-head, each of said devices comprising a casting, and independent springs mounted within the casing.

4. The combination with a binder, of a coupling secured thereto and inclined with relation to the binder, a tongue having an inclined portion slidably supported in said coupling, means for adjustably securing the tongue with relation to the coupling, a draw-head slidably engaging the tongue, means for limiting the movement of the draw-head with relation to the tongue, arms projecting laterally and in opposite directions from the draw-head, and compensating devices adjustably connected with said arms at their forward ends, the rear end of one of said devices being connected with the binder, and an arm projecting laterally from the coupling to receive the rear end of the other compensating device.

5. The combination with a binder, of a coupling secured thereto, a tongue adjustably supported in the coupling, a draw-head slidably engaging the tongue and supporting the draft-eveners, and compensating devices connected to the binder and to the draw-

head, and a truck connected to the binder and adapted to support the same in the absence of draft on the tongue.

6. The combination with a binder, of a coupling secured thereto, a tongue supported in the coupling, draft-evener-supporting means carried by the tongue, a compensating device connected to said means and to the binder, and a second compensating device connected to said means and to the coupling, the latter compensating device being of relatively less normal strength than the first-mentioned compensating device.

7. The combination with a binder, of a coupling secured thereto, a tongue adjust-

ably supported in the coupling and projecting rearwardly therebeyond, draft-evener-supporting means carried by the tongue, a guide carried by the binder and formed with a curved guideway of approximately triangular shape in transverse section, and an arm carried by the rear end of the tongue and formed with a projection for movable reception within said guideway.

In testimony whereof I affix my signature in presence of two witnesses.
